UNITED STATES PATENT OFFICE

148,164

DESIGN FOR A DISPLAY STAND

Eugene Hollander, San Francisco, Calif., assignor to K. Arakelian, Inc., a corporation of Califfornia

Application June 25, 1946, Serial No. 131,017

Term of patent 14 years

(Cl. D80—9)

To all whom it may concern:

Be it known that I, Eugene Hollander, a citizen of the United States and a resident of the city and county of San Francisco, State of California, have invented a new, original, and ornamental Design for a Display Stand, of which the following is a specification, reference being had to the accompanying drawing, forming a part thereof:

Figure 1 is a perspective view of a display stand showing my new design, the stand being symmetrical throughout; and

I claim:

The ornamental design for a display stand, as shown.

EUGENE HOLLANDER.
